UNITED STATES PATENT OFFICE

2,575,014

PRODUCTION OF ALIPHATIC DI-KETONES

Edwin George Edward Hawkins, Lower Kingswood, Tadworth, England, assignor to The Distillers Company Limited, Edinburgh, Scotland, a British company

No Drawing. Application April 5, 1949, Serial No. 85,709. In Great Britain April 29, 1948

6 Claims. (Cl. 260—593)

1

The present invention is for a process for producing aliphatic di-ketones, in particular long chain di-ketones, and their derivatives by the treatment of peroxidic compounds, and to compounds produced thereby.

It is known that hydroperoxides on reacting with ferrous sulphate yield ketones. Hock and Lang have described in Ber. 75 (1942) 1051 and Ber. 76 (1943) 1130 that the hydroperoxides of indane and octa hydroanthracene react when heated with aqueous ferrous sulphate solution and are decomposed catalytically with the formation of ketones which possess the same number of carbon atoms. The same applies to ethylbenzene hydroperoxide which yields acetophenone on being heated with an aqueous ferrous sulphate solution (ibidem 76 (1943) 172).

It has now been discovered in accordance with this invention that hydroperoxides of compounds wherein the peroxide group is attached to a tertiary carbon atom, which forms part of the saturated alicyclic hydrocarbon ring of cyclopentane or cyclohexane and at the same time, is linked to an alkyl group attached to said ring, react with ferrous compounds with the production of di-ketones. Fission of the linkage between the tertiary carbon atom and an adjacent carbon atom in the ring takes place and at the same time identical radicals link up together so that di-ketones with double the number of carbon atoms in the molecule are formed. The following formula for methyl cyclopentane hydroperoxide illustrates the reaction occurring:

The principal object of the invention is to produce a simple process for the production of such di-ketones and to produce useful products thereby.

The invention accordingly comprises the novel products as well as the novel processes and steps of processes according to which such products are manufactured, the specific embodiments of which are described hereinafter by way of example and in accordance with which it is now preferred to practice the invention.

Accordingly the process of this invention for the production of aliphatic di-ketones comprises

2

reacting with a solution of a ferrous salt a hydroperoxide of an alkyl substituted alicyclic hydrocarbon ring selected from the group consisting of cyclopentane and cyclohexane wherein the peroxide group is attached to a tertiary carbon atom which forms part of said hydrocarbon ring and which is also attached to said alkyl group, the di-ketones produced having twice as many carbon atoms as the said ring compound.

10 A suitable ferrous salt is, for instance, ferrous sulphate, which is preferably used in aqueous solution. Other ferrous salts are, for example, ferrous chloride, ferrous acetate, ferrous lactate. Alicyclic hydrocarbons, the hydroperoxides of which may be subjected to the treatment of the present invention and thereby yield di-ketones, are for instance but without limitation thereto, methyl cyclopentane, ethyl cyclopentane, propyl cyclopentane, isopropyl cyclopentane, methyl cyclohexane, ethyl cyclohexane, isopropyl cyclohexane. The proportion of the components of the reaction may vary.

15 The process according to this invention may be carried out by bringing the hydroperoxide of the said alicyclic hydrocarbons into intimate contact with for instance, ferrous sulphate, preferably in aqueous solution. Alternatively, the reaction may be carried out with a solution of the hydroperoxide for instance in the unchanged alicyclic hydrocarbon which contains only a small percentage of the hydroperoxide. Such solutions are obtained in the well known way for instance when the alicyclic hydrocarbon is oxidised by means of molecular oxygen for the preparation of its hydroperoxide without separating the latter from the unchanged hydrocarbon. In this case, it is preferred to treat the hydroperoxide-containing reaction mixture resulting from the oxidation process with water or a solution of dilute alkali in order to remove any acidic impurities formed during the oxidation previous to contacting said mixture with the ferrous salt according to the process of this invention.

20 The process of the invention may be successfully carried out in neutral, alkaline or acid solution. When working in alkaline solution the hydroperoxides are converted into their alkaline salts to which is added the ferrous salt preferably in aqueous solution. It is preferred, however, to carry out the reaction in acid solution, preferably acidified by mineral acid such as sulphuric acid. The amount of acid is conveniently such as to prevent the iron from being precipitated.

25 The reaction of the hydroperoxides according to the process of this invention is exothermic so

that generally no external heating is required. When, for instance, methyl cyclopentane hydroperoxide (in the isolated state) which is a liquid is shaken at ordinary temperature with an aqueous ferrous sulphate solution the mixture warms up and the solid dodecanedione-2:11 separates out and may be recovered directly by filtration. When a solution of the hydroperoxide in unreacted hydrocarbon such as the crude oxidate, is treated according to the present invention the di-ketone formed may be separated by, for instance, decanting the organic solution from the aqueous phase and subsequently distilling the organic solution whereby unreacted hydrocarbon which served as a solvent, distils off. With the hydrocarbon any alcohols and/or mono-ketones which are present in the reaction mixture distil over as well. From the residue the di-ketone crystallises out or may be precipitated therefrom by the addition of a liquid for instance petrol ether in which the di-ketone is insoluble.

As by-products of the reaction with the ferrous salt according to the invention, alcohols and mono-ketones are produced. In the case of methyl cyclopentane hydroperoxide the ketone formed as such a by-product is mainly methylbutyl ketone. These alcohols and mono-ketones may be removed if desired by distillation. The ferric compounds produced during the reaction by oxidation of the ferrous compounds may be reconverted to ferrous compounds by reduction, for instance with sulphur dioxide.

The di-ketones produced according to the process of this invention may be used for the preparation by oxidation of di-basic acids such as sebacic acid, suberic acid and the like.

The following examples illustrate the manner in which the process of the invention may be carried out in practice the quantities given being parts by weight.

Example 1

25 parts of methyl cyclopentane hydroperoxide were shaken at room temperature with 100 parts of water in which 62 parts of crystalline ferrous sulphate had been dissolved. The temperature of the reaction mixture rose considerably whilst a brown iron hydroxide deposit settled out. The reaction mixture after having been cooled was extracted with ether. After removal of the ether the residue was distilled and yielded 8 parts of a fraction consisting of alcohols and mono-ketones and containing a major proportion of methyl butyl ketone and a fraction which yielded 11 parts of dodecanedione-2:11 together with some residue.

The dodecanedione-2:11 had a melting point of 67.5° to 68.5° C. It has been referred to only once previously in the literature by Cason and Prout (J. A. C. S. 66 (1944) 46) as a by product obtained in a very small amount in the preparation of ethyl 10-keto-hendecanoate.

Example 2

20 parts of methyl cyclohexane hydroperoxide were heated on a water bath for 3 hours with an aqueous solution containing 50 parts of crystalline ferrous sulphate. The product was ether extracted and distilled. A fraction containing ketones and alcohols was obtained, weighing 15.0 parts, whilst 1.7 parts of a fraction consisting mainly of tetradecanedione-2:13 was obtained. This di-ketone is insoluble in water, and soluble in most organic solvents. It crystallises in white shining leaflets with a M. P. of 76-77° C.

Example 3

10 parts of methylcyclopentane hydroperoxide (87.2% pure) dissolved in 10 parts of ethanol were added slowly with stirring to a solution of 5 30 parts of crystalline ferrous sulphate, 7 parts of sulphuric acid, 32 parts of ethanol, and 70 parts of water. 4.4 parts of dodecanedione-2:11 were obtained which was isolated by filtration. A similar experiment in which the sulphuric acid was omitted yielded only 3.2 parts of dodecanedione.

Example 4

15 10 parts of methylcyclopentane hydroperoxide (95.6% pure) was converted into its sodium salt by dissolution in the calculated quantity of 10% sodium hydroxide solution, and the aqueous solution so obtained was added slowly with stirring to a solution of 30 parts of crystalline ferrous sulphate made up to 100 parts with water. The 20 precipitated iron hydroxide was dissolved by acidification, and the organic product was isolated by extraction with ether. 2.9 parts of dodecanedione-2:11 and 2.6 parts of a fraction consisting of alcohols and mono-ketones were thereby obtained.

25 Equivalent quantities of ferrous chloride, ferrous acetate and ferrous lactate may be used in the examples to replace ferrous sulphate, the other conditions remaining the same.

I claim:

1. A process which comprises reacting with a solution of a ferrous salt in the presence of some water, a hydroperoxide of an alkyl substituted saturated alicyclic hydrocarbon ring selected from the group consisting of cyclopentane and cyclohexane wherein the peroxide group is attached to a tertiary carbon atom which forms part of said hydrocarbon ring and is also attached to said alkyl group, the di-ketone produced having twice as many carbon atoms as the said ring compound.
2. A process according to claim 1 wherein the solution of the ferrous salt is an aqueous solution of ferrous sulphate.
3. A process according to claim 1 wherein the reaction is effected under acid conditions.
4. A process according to claim 1 wherein the hydroperoxide is methyl cyclopentane hydroperoxide.
5. A process according to claim 1 wherein the hydroperoxide is methyl cyclohexane hydroperoxide.
6. A process which comprises reacting the oxidate solution resulting from reacting the alkyl substituted saturated alicyclic hydrocarbon ring selected from the group consisting of cyclopentane and cyclohexane with molecular oxygen to convert part of said hydrocarbon into the corresponding hydroperoxide so that unreacted hydrocarbon is present, with aqueous ferrous salt solution and recovering the di-ketone produced thereby from its solution in the unreacted hydrocarbon.
